UNITED STATES PATENT OFFICE.

FRITJOF OLANDER AND VIKTOR MOISIO, OF AANEKOSKI, FINLAND.

MANUFACTURE OF PAPER.

Application filed August 25, 1923. Serial No. 659,387.

To all whom it may concern:

Be it known that we, FRITJOF OLANDER and VIKTOR Moisio, residing at Aanekoski, in the Republic of Finland, citizens of the 5 Republic of Finland, have invented certain new and useful Improvements in the Manufacture of Paper, of which the following is a specification.

The present invention relates to the manufacture of paper, and has for its object to improve the method of applying the filling stuff or media during the process of making paper so that loss of such filling stuff is reduced to the smallest possible degree. The 15 invention also relates to apparatus for use in carrying out the improved method or process.

In paper making according to methods heretofore employed, the filling stuff or media for the paper is added either in solid or in liquid form to the Hollander machine, or to the material in the pulping engine or in the pulp vat, and the portion of the earths and pulp which has been withdrawn with the water running from the wet pulp is conducted back again directly to the pulp after the latter has left the pulp vat and while it is passing over the paper machine.

30 Now, according to the present invention all the filling stuff or media is added in liquid form to the pulp web on the wire cloth of the paper machine, and by such method of application it is found that only a small amount of the filling stuff or media is lost; seldom more than 10%. Furthermore the 35 paper receives on both sides a lasting good glaze and is less transparent than paper treated in the known way.

40 It is evident that the filling stuff or media employed may vary in its composition and degree of liquidity, and the principle of application is therefore not limited to any one class of filling stuff or media.

45 In order to maintain a minimum loss of filling stuff, the said stuff has to be added at such a point on the wire cloth, that the suction boxes are only able to suck the stuff through the paper, but not out of it.

50 Depending partly on the thickness of the paper, and partly on the number of the suction boxes, the filling stuff may be added to the paper either on top of, or in front of, or after the first suction box.

55 It is evident that the means whereby the filling stuff can be added to the pulp web

may vary widely as to construction, action and shape. All such considerations are included providing they possess the characteristic features of the invention. 60

On the accompanying drawings there is shown one example of apparatus by means of which the filling stuff may be added to the pulp web, after the said stuff has first been dissolved in water in any known way, 65 for instance, in a common solution reservoir, and diluted with water in a dilution reservoir, which reservoirs of course have to be provided with a sieve, a mixer, and pipes.

Fig. 1 is a front view of the apparatus. 70

Fig. 2 is a plan, and

Fig. 3 is a cross section.

The main portion of the apparatus is a reservoir box 1, which is placed on the top of the paper machine and reaches right 75 across it. The bottom 2 of the box slopes from the centre to both ends, so that the solution is kept in continuous motion. The wedge shaped block 3 comprises a base 3^a secured to the bottom of the box 1, a side 80 wall 3^b enclosing a trough for the liquid filling stuff, and an angularly inclined edge 3^c over which the solution of filling stuff flows in an evenly thick stream over the whole length of the apparatus towards the 85 gate 4. For this purpose the block 3 is fashioned with a vertical wall 3^d, and between this vertical edge and the surface of the gate 4, the filling stuff descends. The space between the edge 3^d and the gate 4, 90 may, for instance, be 10 centimeters high and 3 or 4 millimeters wide.

The ends 6 of the gates 4 are provided with adjusting set screws by means of which the gates may be raised or lowered so that 95 the width of the gap between the gate and the tongue 7 increases or decreases. The gate and the tongue must, of course, be accurately adjusted and ground. The tongue is arranged beneath the gate and the filling 100 solution runs constantly alongside its whole sloping surface evenly over the whole width of the pulp web.

By adjusting the gate in the vertical direction more or less filling solution is spread 105 over the web. The width of the stream may be regulated by means of the adjusting plates 8 to conform to the width of the pulp web.

The whole apparatus is secured by means 110 of beams 9 and 10 to the frame of the paper machine, or to special frames on the sides

of the paper machine. The filling stuff solution is conducted by means of one or more pipes to the box 1 from which it flows on the pulp web, in the way and manner described.

We claim:

Apparatus for applying liquid filling material to the pulp web on the wire cloth of a paper machine, comprising a box or 10 reservoir supported from the paper machine, a base member sloping from its centre to both ends, a wedge shaped block secured to the reservoir or box, an adjustable

gate between which and the block is formed a vertical slot for regulating the flow of ¹⁰ the filling material, and a tongue over which said material flows in a stream on to the pulp web on the wire cloth of the machine.

In testimony whereof we have affixed our signatures in presence of two witnesses.

FRITJOF OLANDER.
VIKTOR MOISIO.
